PACKAGE

Howard Nelson Moore, Washington, D. C., assignor of one-half to Mrs. Howard Kirkpatrick Moore, Washington, D. C.

Application March 24, 1937, Serial No. 132,839

13 Claims. (Cl. 206—56)

The present invention concerns the packaging of a number of relatively small objects or articles. It is an object of the invention to provide a package of a number of articles individually wrapped.

It is an object of the invention to provide a package containing a number of articles each of which is sealed against contamination in a sanitary and hygienic manner.

It is an object of the invention to provide a package in which all the contents are individually sealed and wherein the removal of one article does not expose any of the other articles.

It is an object of the invention to provide a spiral wrapper for mints, lozenges, medicaments or any objects which lend themselves to this type of package, whereby the strip is wrapped about the articles in a tight spiral such that by folding portions of the wrapper strip between the individual articles, these articles are separated from each other and individually packaged. This wrapper strip, which may be of any well-known wrapping material such as paper, treated or otherwise, metal foil, regenerated cellulose, or any protein base material or equivalents.

In the drawing wherein like numbers refer to like parts—

Fig. 1 is a plan view of a portion of one form of wrapper strip.

Figs. 2, 3 and 4 are modifications of the strip shown in Fig. 1.

Fig. 5 is a perspective view of the wrapper strip shown in Fig. 1 applied to a package of candy mints.

Fig. 6 is a perspective view of a plain wrapper strip without.

An elongate wrapper strip 10 made of wax paper, metal foil, Cellophane or the like and having a width much smaller than its length is provided at one edge with slits 11 forming tongues 12. The articles to be wrapped are assembled and the strip 10 wrapped about the first one with the tongue portions 12 extending upward. The strip 10 is wrapped at an angle to the plane of the objects 13 so that it forms a helix as shown by lines 14. This helix 14 may be as flat or as extended as is desired depending upon the thoroughness of the wrap required. It may well be flatter than shown in Fig. 5. As the strip moves upward along the side of articles 13 due to its helical formation, tongues 12 extend above the upper surface of the first of articles 13. This projection of the tongues 12 increases more and more as the wrapper 10 is wrapped about the article. The tongues 12 are bent over as shown at 15 so as to cover the upper surface of the wrapped

article. Where the article has a center hole the tongues may be made long enough to cover the inner surface of such aperture. This spiral wrapping of strip 10 and the folding down of tongues 12 is continued until the entire upper surface of the first article is covered to the extent desired. The second article is then superimposed upon the first but is separated therefrom by the folded tongues 12. At the time the second article is 10 put in position there is an upstanding tongue such as 16 which may act as a guide together with adjacent unbent tongues to center or position the second article. Strictly speaking, 16 is not such a tongue because the top article in Fig. 5 15 has not been completely covered. The wrapping is continued until the tongues 12 again begin to appear above the upper surface of the second article. This may be at once or delayed a portion of a rotation depending upon the relative 20 width of the wrapper 10 as compared with articles 13 and the lead of the helix. The tongues are again folded in as above described and the operation continued until the desired number of articles are wrapped in the package. In this way 25 all of the articles are individually wrapped and both ends of the package covered. If it is desired, an additional cylinder wrap may be placed around the wrapped strip 10.

If desired strip 10 may be provided with a wax 30 coating or may be made of heat sealed Cellophane or the like and the entire package sealed with one application of heat or sealing material. Of course the folds, tongues and laps may be 35 bent or otherwise sealed as the package is built up if desired. If desired an opening string or ripping means may be provided at one end. The spiral may be flattened off and after the top article is covered one of the tongues 12 may be 40 allowed to project as a tearing tip. Again, a tearing string may be included. When the package 45 is opened from this end the strip 10 may be easily unspiralized and the objects removed as desired. If however, the package should be opened from the other end, all of the objects are still individually wrapped and none are unnecessarily exposed even though the package may be less easily opened.

If desired the tongues 12 may be made of sufficient length to reach the center of an article 50 where it has no center hole. The width of the strip is such as to allow for the required length of tongue necessary, for the thickness of the article to be wrapped and an overlap with the article next below.

Fig. 3 has slits 17 along one edge at an angle

thereto. This angle is such that upon being folded over the tongues may be folded radially at all times. The departure of the slits 17 from a perpendicular with the edge 18 is exaggerated in Fig. 3.

Fig. 4 discloses another modifacaton wherein score lines 19 correspond to the line of fold over the edge of the article for protection purposes. In Fig. 5 it would be the line of fold on the tongues. It follows that Fig. 4 can be combined with any of Figs. 1, 2 and 3. When using Fig. 4 alone and unnotched it is necessary to twist the strip between successive score lines 19. That is, after the first article is wrapped and the strip folded over along line 19 it is found desirable to twist the strip in order to bring the second line 19 to bear on the edge of the second article. However, the strip may be crimped instead of twisted if desired.

Fig. 6 discloses an unscored unslotted wrapper. The folded part is crimped or pleated as at 20. The sharp transition at 21 requires a somewhat larger fold than shown at 20.

The drawing is merely illustrative of one form of the invention and is in no sense to be treated as limiting. The claims are relied upon to indicate the breadth of the patent monopoly.

The use of the present package is not confined to eatables or medicines. It may be found equally applicable to any series of units which it may be desired to package individually in the same package.

I claim:

1. A package comprising a plurality of similar articles, a relatively long, narrow, flexible, helical wrapper, portions of which are lapped, wrapped tightly around the outer edges of said articles, portions of said lapped portions being positioned between adjacent articles, forming means separating an article from one next adjacent.

2. A package comprising a plurality of similar articles, a relatively long, narrow, flexible, helical wrapper wrapped around the outer edges of said articles, portions of said wrapper being bent away from the helical surface and positioned between adjacent articles as said wrapper is wound about said articles whereby separating means are formed, the division between articles being covered by a succeeding turn of the wrapper.

3. A package, a number of similar superposed articles therein, a thin long narrow flexible wrapping strip wound in a helix about said articles, portions of said strip being bent out of the helical surface along the edges of said articles and positioned between adjacent articles said portions separating one article from another and forming a partition extending completely across said package in all directions whereby each article is completely individually wrapped and the entire package is wrapped by the same wrapper.

4. The combination set forth in claim 3, said bent portions of said strip being articulate tongues formed in one edge thereof.

5. A package, a number of similar superposed articles therein, a thin, long, narrow, flexible wrapping strip having a substantially continuous linear edge extending substantially throughout the length of said strip and wound in a helix about said articles, portions of said strip along

the opposite edge being bent over said articles and positioned between adjacent articles whereby said articles are separated from each other.

6. A package comprising a plurality of articles 5 in side by side relationship, a helical wrapper, portions of which are folded over and upon individual articles, the amount of said folded portions increasing as the wrapper progresses around an article until a base is formed for the succeeding article which is wrapped in turn.

7. A package comprising a plurality of similar 15 individually wrapped articles in side by side relationship, a relatively long, narrow, flexible, helical wrapper edge portions of which are folded over and positioned between adjacent articles 15 in such a manner that said portions form separating partitions with adjacent articles bearing against the respective sides of said partitions whereby each article is separately wrapped in an individual compartment of its own.

8. A package comprising a plurality of articles, 25 a single elongate wrapper sheet helically wrapped around outer portions of said articles, portions of said wrapper sheet being progressively folded over an inner portion of each article as the helical wrapper sheet passes from one article to another and separating the articles one from another by forming a wall between adjacent articles.

9. A package comprising a plurality of similar 30 individually wrapped articles in side by side relationship, a relatively long, narrow flexible wrapper wrapped in a relatively tight helix about the outer portions of an article and progressing along it, some of the wrapper which extends beyond the outer portions of the said article being bent to cover an inner surface portion of said article and form a base upon which the next article may rest, said wrapper continuing in its helical formation about the outer portions of the 40 next article and progressing along it, an inner surface portion of said second article being in turn covered by bent portions of said wrapper in increasing amount as it advances, said wrapper continuing on to the next article and the next 45 whereby the wrapper provides a series of separate sanitary cubicles having dividing walls integral with the wrapper and formed by it.

10. A package comprising a plurality of similar 50 articles in side by side relationship, a relatively long, narrow, flexible, helical wrapper around the outer edges of said articles, portions of said wrapper being positioned between adjacent articles as said wrapper is wound about said articles, said portions being covered by a succeeding turn of 55 the helix whereby separating means are formed and the outer surface of said package is substantially imperforate.

11. The combination set forth in claim 1, said 60 portions positioned between adjacent articles comprising tongues cut in an edge of the wrapper sheet.

12. The combination set forth in claim 1, an edge of said wrapper sheet having slits cut therein.

65 13. The combination set forth in claim 1, an edge of said wrapper sheet having notches cut therein.

HOWARD NELSON MOORE.
